EMORY W. FENN, OF CHICAGO, ILLINOIS, ASSIGNOR TO THE PEELE COMPANY, OF BROOKLYN, NEW YORK, A CORPORATION OF NEW YORK.

ELEVATOR DOOR.

1,424,287.

Specification of Letters Patent.

Patented Aug. 1, 1922.

Application filed December 13, 1919. Serial No. 344,724.

To all whom it may concern:

Be it known that I, EMORY W. FENN, a citizen of the United States, residing at Chicago, in the county of Cook and State of Illinois, have invented certain new and useful Improvements in Elevator Doors, of which the following is a specification, reference being had therein to the accompanying drawings, which form a part thereof.

10 My invention relates to elevator doors, and more particularly to a door of this character known as a "pass type" door wherein the door openings of adjacent floors are each closed by a door composed of two sections, 15 oppositely movable in parallel vertical planes, the upper section of one door being spaced away from the wall of the shaft to afford clearance for the lower section of the other door, thus permitting the adjacent sections to pass each other when opening or closing either of said doors.

Heretofore in this art doors of the pass type have had the two sections mounted upon parallel straight tracks, the upper section of each door being spaced away from the wall of the elevator shaft sufficiently to permit the passage of the lower section of the door above between it and the door opening, or to permit the upper section of one 30 door to pass the lower section of the closed door above it on the shaft side thereof.

In the type of door to which I have above referred, a pivotal shield is used to close the gap between the upper door section and the 35 wall of the shaft when any door is closed. This construction, however, is not desirable, as it does not secure a sufficiently tight closure of the door opening to guard against passage of smoke and flames in the event of 40 fire, and does not afford sufficiently rigid locking means when the doors are closed to prevent displacement of the doors under the force of blows thereon. Furthermore, it requires a double guide rail structure through- 45 out the shaft.

The pass type of door is employed where the clearance between the lintel of one door and the sill of the door immediately above is not sufficiently great to permit the use of 50 doors, the sections of which have movement in the same vertical plane, known as regular

type doors. Conditions are sometimes such that it is essential to use the pass type of door throughout an entire shaft, and sometimes such that this type of door may be used 55 at some openings and the regular type doors at other openings.

My present invention has to do with an elevator door structure wherein each of two adjacent doors has one section of the pass 60 type and the other section of the regular type, thus permitting the application of a pass type door embodying my invention to one particular floor of a building wherein the clearance between door openings is not 65 sufficient to permit the use of a regular type of door at that particular floor.

A door made in accordance with my present invention employs a single guide rail at each side of the door, which is so formed 70 that one of the door sections, when opening and closing the door, will have a directly vertical movement, while the other section will have a combined vertical and horizontal movement, the two door sections, when the 75 door is closed, being brought into the same vertical plane.

It is essential that the lower section of one door and the upper section of the adjacent door be so constructed and mounted that 80 either will pass the other as a result of the combined horizontal and vertical movement above referred to.

Upon the wall rail which carries the guide rail, I provide suitable guides co-operating 85 with a supplemental shoe upon the pass type door section, which will ensure a horizontal parallel movement of the door during its vertical travel, and I associate therewith what may be termed an automatic switch 90 mechanism which will ensure a return parallel movement upon the closing of the door. This switch mechanism also acts as a binder to hold the door section against horizontal displacement adjacent the sill and the lintel 95 thereof, when the doors are in the closed position.

The two sections of a door are connected by a chain, cable or other flexible connection, so as to ensure their simultaneous movement 100 in opposite directions, it being essential to so arrange the pulley over which this con-

nection passes, and to so construct the wall rail as to permit the proper freedom of movement of this flexible connection in adjusting itself to the horizontal component of motion of the door section of the pass type.

While I employ a single rail, it is essential to provide a gap in that portion of the rail most remote from the wall of the shaft, through which a special guide shoe may pass so as to provide suitable guides adjacent the top and bottom door sections when the special guide passes out of the operative range of the guide member carried by the wall rail.

I also utilize said guide member co-operating with the pass type upper section of a door, as a positive stop to prevent the falling of this section in the event of breakage of the flexible connection.

The invention consists primarily in an elevator door embodying therein two door sections, one of which when opening and closing has a vertical movement only, and the other of which has a vertical movement and a horizontal component of movement, and a single guide rail for both of said sections; and in such other novel features of construction and combination of parts as are hereinafter set forth and described, and more particularly pointed out in the claims hereto appended.

Referring to the drawings,

Fig. 1 is a vertical section of a portion of an elevator shaft embracing two door openings and a door structure at each opening, both doors being closed,

Fig. 2 is a similar view with the lower door open;

Fig. 3 is a detail view upon a larger scale of the door structure at the upper openings shown in Figs. 1 and 2, with the door in the closed position;

Fig. 4 is a plan view of Fig. 2 upon an enlarged scale; and

Fig. 5 is a detail perspective view of one upper corner of the upper section of the lower door in Figs. 1 and 2, showing the relation of the upper guide shoe upon said section, and the guide carried by the wall rail.

Like letters refer to like parts throughout the several views.

Since the arrangement of the guide rail and its associated guides and switches, and the construction at each side of the door, is duplicated upon opposite sides of the door opening, and of the door sections, a detailed showing of but one side of the door structure and of the guide rails at one side of the door opening, and a detailed description of the structure of one side of the door will be entered into.

In the embodiment of the invention shown in the drawings, the upper door opening of a portion of a shaft containing two doors,

is shown at A, and the lower door opening at B. The lintel line of the door A is indicated at *a* and the sill line at *a'*, and the lintel line of the door B is shown at *b* and the sill line at *b'*.

Within the shaft on each side of the door opening is a vertically extending wall rail *c* extending throughout the shaft upon opposite sides of the several door openings. This rail differs from the ordinary angle rail now ordinarily employed, merely in the respect that the inwardly extending flange thereof adjacent the lower half of the door opening A, and the upper half of the door opening B is wider than other portions thereof, as shown at *c'*.

Mounted upon each wall rail is a guide rail having two parallel vertical sections *d*—*d'* connected by oblique sections *d*², the section *d'*, extending from adjacent the lower part of the door opening A to adjacent the upper part of the opening B, being more remote from the wall of the shaft than the section *d*, and the sections *d*² connecting said sections *d* and *d'*. This guide rail structure therefore presents the characteristic of a single rail having two sections extending in parallel vertical planes connected by oblique sections, the purpose of which will more fully appear hereinafter.

The door opening A is closed by means of a door comprising an upper door section *e* provided with the ordinary guide shoes *e'*—*e*² adjacent the top and bottom thereof respectively, and co-operating with the section *d* of the guide rail upon which it has vertical movement in one plane only; and a lower section *f* mounted to have movement upon the sections *d* *d*² and *d'* of said rail by means of upper guide shoes *f'*, a lower guide shoe *f*², and a supplemental guide shoe *f*³ intermediate said shoes, so as to have a combined vertical and horizontal movement. The section *f*, when the door is closed, occupies the same plane as the section *e*, but a plane parallel therewith and spaced away therefrom sufficiently to pass the upper section of the door closing the opening B when the door is open.

Mounted upon the portion *c'* of the wall rail *c* and adjacent the sill *a'*, is a fixed guide member *g* having an inclined face presented inwardly and upwardly of the shaft, said guide member being located in the path of movement of the shoe *f*³ so as to co-operate with the section *d*² and the shoes *f'* when imparting the desired horizontal component of movement to the door section *f*. Also carried by the rail *c* and co-operating with the shoe *f*³ is a pivotal guide or switch member *h* mounted adjacent the guide *g*, the purpose of which is to hold the lower door section *f* closely adjacent the wall of the shaft when the door is in the closed position, serve as a guide for the shoe *f*³

when closing the door to ensure its following the guide *g* during this action.

The shoe *f*² is of a length so that when passing between the fixed guide member *g* and movable guide or switch *h*, it will remain in a vertical position and thus avoid any substantial tilting action of the door. The upper part of the pivotal guide or switch member *h* is overweighted so as to 5 be normally out of poise, the two arms of said switch mechanism being of a length, and the ends so formed, that when the door is open, the upper end will bear against the wall flange of the wall rail *c*, and the lower 10 end will bear against the guide rail *d'* so as to hold this member in a position where the horizontal movement of the door, in closing, will be assured and possible displacement of the member and a resultant jamming of the door will be avoided.

The two door sections *e* and *f* are connected by a flexible cord or strand *i* passing over the sheave *i'* carried by a fitting adjacent the lintel of the door opening *A*. The 25 connection *i* is secured to an offset fitting *e*³ adjacent the bottom the door section *e*, and the other end thereof is connected to an offset fitting *f*⁴ adjacent the top of the lower section *f*.

30 Carried by the side rail *c* is a stud *h'* against which the shoe *f*³ forces said guide member *h* as the door comes to the closed position, all stresses upon the door being transferred to said stud through said pivotal 35 guide or switch member *h*.

To secure the desired clearance for the shoe *f*², this shoe is offset from the bottom of the section *f* so as to be normally positioned below the guide member *g*, and thus 40 avoid interference therewith.

Since when the lower door section *f* is of the pass type, it will, when the door is open, be spaced away from the sill of the door opening by slightly more than the thickness 45 of a door section, I provide the top of said section with a truck bar *f*⁵ of sufficient width to project from said section when it is in the fully open position, across the space between it and the sill of the door, and thus 50 avoid the presence of a gap into which the wheels of trucks might drop when passing to and from an elevator car. The section *e* is provided with an offset astragal *e*⁴ adapted to receive the offset truck bar *f*⁵. Since a 55 door is seldom more than two inches in thickness, said truck bar and said astragal will not seriously interfere with conditions about a door, even though, when a door is closed, they project within the door opening.

60 The door closing the opening *B* is composed of an upper section *j* mounted upon the sections *d*, *d'* and *d*² of the guide track so as to have simultaneous vertical and horizontal movement, and the lower section *k* 65 mounted upon the section *d* of said track.

The section *j*, like the section *f*, is provided with shoes *j'* constantly engaging the track, which shoes correspond with the shoes *f* upon the section *f* of the door immediately above the section *j*. Said section is also 70 provided with an offset guide shoe *j*² similar to the shoe *f*² upon the section *f*, and a supplemental guide shoe *j*³ corresponding in function with the shoe *f*³.

The section *k* is provided with guide shoes 75 *k'* and *k*² corresponding with the shoes *e'* and *e*² upon the section *e* of the door heretofore described.

Carried by the wall rail *c* is a guide member *m* corresponding with the guide member 80 *g*, but differing therefrom in that its position is inverted, since it must cooperate with an upwardly moving door instead of a downwardly moving door. The member *m* is provided with a bridge *m'* adapted to be 85 engaged by the shoe *j*² when the door closing the opening *B* is in the closed position, thus preventing the falling of the section *j* in the event of breakage of the cables connecting it and the section *k*.

90 Mounted adjacent the guide member *m* is a pivotal guide member or switch *n* which is overweighted so as to have a normal tendency to drop away from the guide member *m*, said member *n* having a heel *n'* adapted 95 to engage a stud *n*² carried by the wall rail *c*, so that any stresses applied to this section from the floor side of the opening will be transmitted through the shoe *j*³ and said heel *n'* to said stud, and thus prevent displacement 100 of the door.

When the upper door section only has vertical and horizontal movement, the truck bar and astragal construction heretofore described cannot be used, so that such doors 105 may be equipped with the ordinary astragal, the top of the lower section itself serving as the truck bar and not requiring any offsetting thereof in the manner heretofore described. The manner of connecting the two 110 doors is as described above, the sheave *i'* of each door structure having its axis parallel with the wall of the shaft adjacent the door opening so as to compensate for the horizontal component of movement of one of the 115 door sections whenever the pass type construction heretofore described, is used.

It will be observed that in both the upper door structure and the lower door structure shown in Figs. 1 and 2, the door section of 120 the pass type has one shoe which is in constant engagement with the guide rail, and another shoe which is normally disengaged therefrom, or disengaged therefrom when the door is in the closed 125 position. To ensure the desired accuracy in the functioning of the door, it is desirable to employ this shoe normally disengaged from the guide rail and to so proportion the various parts that when the door has 130

attained its maximum horizontal movement, this shoe will engage the guide rail section d' , an arrangement which necessitates the formation of a gap in said rail intermediate 5 the two door openings, to permit the passage of the shoe to a position where it will automatically engage the rail so as to stabilize the door section during its further vertical movement. Such a gap is indicated at c^2 10 in the drawings.

The operation of the herein described door structure is substantially as follows:—

In Fig. 1 of the drawings, the doors at the 15 openings A and B are both shown as being closed, while in Fig. 2 the door at the opening B is shown as being opened. In describing the operation, I will first refer to what occurs when a door at the opening B is 20 opened and closed, and then give a similar description of the action of the door A under the same conditions.

By reference to Fig. 1, it will be observed 25 that the guide rail section d adjacent each door opening, when the doors are closed, will hold the door section having directly vertical movement thereon, in close juxtaposition to the wall of the shaft, and that the other section of each door, such section being of the 30 pass type, will have that edge thereof adjacent the middle of the door opening, held in close juxtaposition to the wall of the shaft by said section d , and the opposite edge thereof similarly held by the movable guide or switch member co-operating with that 35 door, the stud acting upon said guide or switch member limiting the oscillatory movement thereof under the control of the door and transmitting any strains upon the door to the wall rail $c-c'$.

40 The truckable feature of the door so far as the stop mechanism carried by the guide rail is concerned, is old and well known in the art and has therefore not been shown nor described. This is also true of the controlling mechanisms for the doors, since in these respects the door may be of the manually operative, semi-automatic or full automatic type.

In opening the door closing the opening 45 B, the lower section k will have a directly vertical fall, being guided in its movement by the portion of the rail section d co-operating with the shoes k' and k^2 . With the initial movement of the upper section j of this door, the shoe j' will pass from the section d onto the oblique section d^2 , the supplemental guide shoe j^3 by its engagement with the fixed guide member m , the contact surface of which is substantially parallel with 55 that of the section d^2 , causing said section j immediately after its initial movement, to have an upward vertical movement with a horizontal component of movement as determined by the angle of the contact surface of 60 the guide m and of the oblique rail section

d^2 . With the upward movement of the shoe j' , the engagement of the lower end thereof with the movable guide member or switch n will impart a movement thereto sufficient to form clearance space equal to the length of 70 the shoe j^3 between it and the fixed guide m , one end of this shoe being guided by the member m and the other end thereof by the member n . Hence there will be no tilting of either the door section or of the shoe j^3 , the 75 door section at all times occupying a substantially vertical position.

As the section j begins to rise, the offset shoe j^2 carried thereby will leave the bridge m' of the guide m and will pass in an oblique course toward the opening c^2 in the rail section c' . Substantially simultaneously with the passage of the shoe j' from the section d^2 of the guide rail, the shoe j^2 will be brought into a position where it will straddle 85 the rail section d' beyond said gap c^2 , and thus co-operate with the shoe j' in guiding the door section in its further movement. The supplemental shoe j^3 , substantially simultaneously with the engagement of the 90 shoe j^2 with the rail section d' , will pass from its operative relation to the guide members $m-n$, having no further function during the opening movement of the door.

By reason of the overweighting of the 95 guide member n , it will remain in an overbalanced position with the upper end thereof engaging the rail section d' and the lower end thereof engaging the wall flange of the 100 wall rail c , thus so positioning said guide or switch member n that it will receive the supplemental shoe j^3 during the closing movement of the door.

When the door is being closed, the movement of each section j and k thereof will be 105 merely a reversal of that above referred to, the same parts co-operating in the manner above referred to, to guide the section j in its oblique travel toward its position in close juxtaposition to the wall of the shaft adjacent the door opening B.

In opening the door, the movement thereof inwardly of the shaft will be sufficient to cause the section j to pass about the guide member g adjacent the sill of the door immediately above, and past the lower door section f at the door opening A. The extent of the pass movement of the pass type door section is immaterial, it being possible to use a door of this type where the clearance between the lintel of one door opening and the sill of the door opening immediately above, is from fifteen to eighteen inches.

It is to be observed that with a pass type door structure made in accordance with my 125 invention, it is essential that the doors at two adjacent door openings each be so constructed that the adjacent sections of the two doors be of the pass type, it being designed to have the other door sections, and 130

the doors at other openings, of the regular type. Hence my invention contemplates the use of two door structures, one co-operating with the other, which construction is essential, because when the doors are closed they occupy the same vertical plane, and hence while the horizontal component of motion is necessary to secure the clearance for the opening of one door, it is equally true that the same conditions exist as to the adjacent door.

Adverting to the operation of the door closing the opening A, it will be as heretofore described in connection with the door at the opening B, with the exception that the upper door section *e* will have only a vertical movement, while the lower door section *f* will have a vertical movement with a horizontal component under the control of the fixed guide member *g*, the movable guide or switch member *h*, the upper portion of the guide rail section *d*, the upper portion of the offset guide rail section *d'*, and the oblique connecting guide rail section *d''*.

As the section *f* of this door comes to rest, the truck bar *f³* will span the gap between this section and the door sill *a'*, the astragal *e⁴* coming to rest adjacent, but below, the lintel *a*. When the door is closed, said truck bar and said astragal will project within the door opening, but the extent of this projection will not be sufficient to obstruct the space within the door opening.

By using a sheave *i'* having its axis parallel with the wall of the shaft adjacent the door opening, one reach of the connecting strand or cable *i* will be positioned in substantial vertical alinement with the bracket *e³* upon the door *e*, while the other reach will have perfect freedom of movement toward and from the rail *c* without interfering therewith, since the offset bracket *f⁴* will project across the edge of the wall rail *c* and will be caused to follow same by the movement of the door section carrying said bracket. The horizontal movement of the door is so small that this change of position of one reach of the connection between the door sections will have no appreciable effect upon the functioning of the door.

The importance of the arrangement of the sheave *i'* as described results from the fact that if the axis of the sheave were otherwise arranged, said connection would have a tendency to constantly ride upon the edge of the sheave, and thus present a constant likelihood of the falling of the doors.

As the upper section of the door closing the opening B and the lower section of the door closing the opening A come to the fully closed position, the supplemental shoe carried thereby respectively will restore the movable guide or switch member to its normal position where it will be removed

from adjacent the guide rail section *d'*, thus affording clearance for the passage of the co-operating door section of the pass type. The shoe *f³* or *j³* will come to rest engaging one arm of its co-operating movable guide or switch member *h* or *n*, respectively, and forcing it into engagement with its stop stud *h²* or *n²* with the result that this switch member and its co-operating stud in each instance will serve as a binder to hold the door firmly against the wall of a shaft.

It is not my intention, in the present application, to claim broadly an elevator door of the pass type in which a door section or sections have a vertical movement with a horizontal component in opening and closing same, so that the section or sections of one door may pass the section or sections of adjacent doors while being in the same vertical plane when in the closed position. The present invention is limited to an elevator door in which one section only is of the pass type, the other section being of the regular type.

The accompanying drawings are largely diagrammatic, since it is impossible to show the invention clearly with a drawing to scale. Many characteristics of doors of this type which are well known in the art are neither shown nor described, such being immaterial to the present invention.

It is not my intention therefor, to limit the invention to the precise details of construction shown in the accompanying drawings, it being apparent that such may be varied without departing from the spirit and scope of the invention.

Having described the invention, what I claim as new and desire to have protected by Letters Patent, is:

105

1. An elevator door embodying therein two door sections, one of which when opening and closing has a vertical movement only, and the other of which has a vertical movement and a horizontal component of movement, and a single guide rail for both of said sections.

2. An elevator door embodying therein a single guide rail having two sections occupying parallel vertical planes, and a connecting oblique section adjacent each side of a door opening, a door section mounted to have movement upon the vertical section of said rail nearer the door opening, a second door section adapted to have movement upon said last named vertical, said oblique, and said other vertical rail sections, and an inclined guide member operative upon said second door section.

3. An elevator door embodying therein a single guide rail having two sections occupying parallel vertical planes, and a connecting oblique section adjacent each side of a door opening, a door section mounted to have movement upon the vertical section

125

130

of said rail nearer the door opening, a second door section adapted to have movement upon said last named vertical, said oblique, and said other vertical rail sections, 5 an inclined guide member, the operative surface of which is substantially parallel with that of said oblique rail section, a second guide member pivotally mounted adjacent, and having an operative surface adapted to 10 be positioned parallel with but spaced away from the operative surface of said inclined guide member, and a guide shoe carried by said last named door section adapted to operatively engage both of said guide members.

4. An elevator door embodying therein a single guide rail having two sections occupying parallel vertical planes, and a connecting oblique section adjacent each side 20 of a door opening, a door section mounted to have movement upon the vertical section of said rail nearer the door opening, a second door section adapted to have movement upon said last named vertical, said oblique, 25 and said other vertical rail sections, an inclined guide member, the operative surface of which is substantially parallel with that of said oblique rail section, a second guide member pivotally mounted adjacent, and having an operative surface adapted to be 30 positioned parallel with but spaced away from the operative surface of said inclined guide member, and a guide shoe carried by said last named door section adapted to operatively engage both of said guide members, said movable guide member being so 35 positioned as to be engaged by said guide shoe when the door is in the closed position, and a stud adapted to be engaged by said 40 movable guide member, whereby movement of said door section carrying said guide shoe away from the wall of the shaft, is prevented when the door is in the closed position.

5. An elevator door embodying therein a single guide rail having two sections occupying parallel vertical planes, and a connecting oblique section adjacent each side 45 of a door opening, a door section mounted to have movement upon the vertical section of said rail nearer the door opening, a second door section adapted to have movement upon said last named vertical, said oblique, and said other vertical rail sections, and an inclined guide member operative upon said 50 second door section, said rail section more remote from the wall of the shaft having a gap therein, and said second door section having a shoe offset with relation to one horizontal edge thereof adapted to pass through said gap, and to be automatically engaged with and disengaged from the guide rail adjacent said gap with the opening and the closing of the door.

6. An elevator door embodying therein a single guide rail having two sections occu-

pying parallel vertical planes, and a connecting oblique section adjacent each side of a door opening, the guide rail section nearer the wall of the shaft extending adjacent the upper half of the door opening, 70 and said oblique and said other vertical sections extending adjacent the lower part of said opening, an upper door section having guide shoes co-operating with the guide rail section nearer the wall of the shaft, a lower 75 door section having guide shoes co-operating with said last named vertical, said oblique and said other vertical rail sections, an inclined guide member operative upon said lower door section, an offset truck bar 80 carried by said lower door section, whereby when the door is open, said truck bar will span the gap between its door section and the sill of the door opening, and an offset astragal carried by said upper door section 85 and adapted to inclose the edge of said truck bar when the door is closed, said truck bar and said astragal being projected within the door opening when the door is closed.

7. An elevator door embodying therein a single guide rail having two sections occupying parallel vertical planes, and a connecting oblique section adjacent each side 90 of a door opening, the guide rail section nearer the wall of the shaft extending adjacent the upper half of the door opening, and said oblique and said other vertical sections extending adjacent the lower part of said opening, said last named vertical section having a gap therein, an upper door 95 section having guide shoes co-operating with the guide rail section nearer the wall of the shaft, a lower door section having guide shoes co-operating with said last named vertical, said oblique and said other vertical 100 rail sections, an offset shoe carried at the lower edge of said lower door section adapted to pass through said gap and to be automatically engaged with and disengaged from the guide rail adjacent said gap with 110 the opening and the closing of the door, an inclined guide member operative upon said lower door section, an offset truck bar carried by said lower door section, whereby when the door is open, said truck bar will 115 span the gap between its door section and the sill of the door opening, and an offset astragal carried by said upper door section and adapted to inclose the edge of said truck bar when the door is closed, said truck bar 120 and said astragal being projected within the door opening when the door is closed.

8. An elevator door embodying therein two door sections, one of which when opening and closing has a vertical movement 125 only, and the other of which has a vertical movement and a horizontal component of movement, a single guide rail for both of said sections, a sheave adjacent the lintel of a door opening and having its axis parallel 130

with the wall of the shaft adjacent said door opening, and a flexible connection passing about said sheave and having its opposite ends connected with said door sections respectively.

9. An elevator door embodying therein a single guide rail having two sections occupying parallel vertical planes, and a connecting oblique section adjacent each side 10 of a door opening, a door section mounted to have movement upon the vertical section of said rail nearer the door opening, a second door section adapted to have movement upon said last named vertical, said oblique, 15 and said other vertical rail sections, an inclined guide member operative upon said second door section, said guide rail being carried by an angular wall rail, the inwardly projecting flange of which is extended adjacent 20 said oblique rail section and said rail section more remote from the wall of the shaft, an offset bracket carried by each of said door sections and extending across the edge of said wall rail, a sheave adjacent 25 the lintel of the door opening and having its axis parallel with the wall of the shaft adjacent said opening, and a flexible connection passing about said sheave and having its opposite ends connected with said 30 brackets respectively.

10. An elevator door structure embodying therein doors closing adjacent openings in a shaft, the door at the upper opening comprising an upper section having a vertical movement only, and a lower section having a vertical movement with a horizontal component, and the door at the lower door opening comprising a lower section having a vertical movement only, and the 35 upper section having a vertical movement with a horizontal component, and guiding means for said door sections respectively.

11. In an elevator door structure, the combination of a guide rail having aligned vertical sections one adjacent the upper part 40 of one door opening, and the other adjacent the lower part of the door opening immediately below, a vertical section parallel with and arranged intermediate said other vertical sections, and positioned more remote 45 from the wall of the shaft, and oblique sections connecting said last named and said first named vertical sections, an inclined guide adjacent the sill of the upper door 50 opening having an operative surface substantially parallel with the oblique rail section adjacent that door opening, an inclined guide adjacent the lintel of the lower door opening having an operative surface substantially parallel with the oblique rail section adjacent that door opening, doors closing 55 said door openings respectively, the door closing the upper door opening comprising an upper section having movement upon the rail section nearer the door opening, and the lower door opening comprising a door section having movement on the guide rail section adjacent the sill of said lower door opening, and an upper door section adapted 60 to have movement upon said last named vertical rail section, said other vertical section adjacent the lintel of said lower door opening, and the connecting oblique rail section, and a guide shoe carried by said last named upper door section co-operating with the inclined guide adjacent the lintel of the lower door opening having at the upper edge thereof 65

the lower door section having movement upon said last named rail section, the vertical section parallel therewith and the connecting oblique section, a guide carried by said lower door section co-operating with the 70 guide member adjacent the sill of that door opening, and the door at the lower door opening comprises a door section having movement on the guide rail section adjacent the sill of said lower door opening, and an upper door section adapted to have movement upon said last named vertical rail section, said other vertical section adjacent the lintel of said lower door opening, and the connecting oblique rail section, and a guide 75 shoe carried by said last named upper door section co-operating with the inclined guide adjacent the lintel of the lower door opening.

12. In an elevator door structure, the combination of a guide rail having aligned vertical sections one adjacent the upper part of one door opening, and the other adjacent the lower part of the door opening immediately below, a vertical section parallel with and arranged intermediate said other vertical sections, and positioned more remote from the wall of the shaft, and oblique sections connecting said last named and said first named vertical sections, said last named vertical rail section having a gap therein, 95 an inclined guide adjacent the sill of the upper door opening having an operative surface substantially parallel with the oblique rail section adjacent that door opening, an inclined guide adjacent the lintel of the lower door opening having an operative surface substantially parallel with the oblique rail section adjacent that door opening, doors closing said door openings respectively, the door closing the upper door opening comprising an upper section having movement upon the rail section nearer the door opening, and the lower door section having movement upon said last named rail section, the vertical section parallel therewith and the connecting oblique section, a guide carried by said lower door section co-operating with the guide member adjacent the sill of that door opening, and the door 100 at the lower door opening comprises a door section having movement on the guide rail section adjacent the sill of said lower door opening, and an upper door section adapted to have movement upon said last named vertical rail section, said other vertical section 105 adjacent the lintel of said lower door opening, and the connecting oblique rail section, and a guide shoe carried by said last named upper door section co-operating with the inclined guide adjacent the lintel of the lower door opening.

13. In an elevator door structure, the combination of a guide rail having aligned vertical sections one adjacent the upper part of one door opening, and the other adjacent the lower part of the door opening immediately below, a vertical section parallel with and arranged intermediate said other vertical sections, and positioned more remote from the wall of the shaft, and oblique sections connecting said last named and said first named vertical sections, an inclined guide adjacent the sill of the upper door opening having an operative surface substantially parallel with the oblique rail section adjacent that door opening, an inclined guide adjacent the lintel of the lower door opening having an operative surface substantially parallel with the oblique rail section adjacent that door opening, doors closing said door openings respectively, the door closing the upper door opening comprising an upper section having movement upon the rail section nearer the door opening, and the lower door section having movement upon said last named vertical rail section, said other vertical section adjacent the lintel of said lower door opening, and the connecting oblique rail section, and a guide shoe carried by said last named upper door section co-operating with the inclined guide adjacent the lintel of the lower door opening, the lower door section at the upper door opening having a guide shoe offset from the lower edge thereof, and said upper door section closing the lower door opening having at the upper edge thereof 130

an offset guide shoe, said offset guide shoes respectively being adapted to pass through said gap and be automatically engaged with or disengaged from the guide rail, with the opening and the closing of said doors respectively.

In witness whereof I have hereunto affixed

my signature, in the presence of two subscribing witnesses, this 3rd day of December, 1919.

EMORY W. FENN.
